FOOT AND LEG SUPPORT FOR
CHIROPODISTS' CHAIRSFrank Koenigkramer and Frederick
Koenigkramer, Cincinnati, Ohio

Application May 16, 1932. Serial No. 611,468

6 Claims. (Cl. 155—172)

This invention relates to a support for use on a chiropodist's chair, or the like, for supporting the foot and leg of a patient in proper position to be operated upon.

• An object of the invention is to provide such a structure having a wide range of adjustment.

Another object is to provide such means in which the adjustments are quickly and simply effected.

10 Another object is to provide such a device which is readily attachable to and removable from a chair.

Another object is to provide a support having means for sustaining loosened parts during adjustment thereof.

These and other objects are attained by the means described herein and illustrated in the accompanying drawing, in which:

Fig. 1 is a side elevational view of the support 20 of this invention as operatively associated with the step on a chiropodist's chair, or the like.

Fig. 2 is a cross sectional view taken on line 2—2 of Fig. 1.

Fig. 3 is a view taken on line 3—3 of Fig. 1.

25 Fig. 4 is a cross sectional view taken on line 4—4 of Fig. 1.

The fore portion of the swivel or movable part of a chiropodist or similar swivel chair, is indicated at 6 and is provided in the usual way with 30 a downwardly depending leg member 7 having the step 8 secured upon its lower end. The under portion of this step is provided with a pair of bearing blocks 9, each drilled longitudinally, and adapted to cooperate with the support means of this invention.

35 The latter comprise an inverted T joint 10 providing a horizontal sleeve 11 split longitudinally as at 12 along one side thereof. Two ears 13 and 14 are formed integral with the sleeve and are in spaced registration with one another, one on each side of the split 12. A set screw 15 passes through ear 13 into ear 14. A clamping screw 16, provided with a hand wheel 17, passes through both ears. A vertical hollow stem 18 projects upwardly of and communicates with the interior of sleeve 11.

40 A pair of stub shafts 19 and 20, the inner portions of which may be hollow as seen in Fig. 2, is journaled one in each end of sleeve 11 and projects outwardly thereof. The projecting outer ends 21 and 22 of these shafts are solid and each formed with a transverse bore within which is removably fixed, by means of a set screw 23, the outer end of one of a pair of support rods 24 and 25. The rods 24 and 25 are adapt-

ed to be slidably received, one each in a suitable bearing block 9 on the bottom of the chair step 8. Said rods extend in spaced, substantially parallel relationship with the supporting surface whereon the chair rests and holds the T joint and the whole foot support structure in position. By pulling out or pushing in the T joint on its 60 slideable rod mounting, the distance of said joint from the chair may be varied.

An upright shaft 26 extends through and projects upwardly of stem 18. The lower end of shaft 26 extends transversely through sleeve 11 between the inner ends of stub shafts 19 and 20 and outwardly of an aperture 27 provided in the bottom of sleeve 11.

65 A U-shaped bracket 28 is fixed upon and projects upwardly of the upper end of shaft 26, and is formed with arms 29 and 30 which form a swivel mounting for a foot and leg supporting cushion member 31. The latter may be pivotally moved and secured in a desired position relative to arms 29 and 30 by means of a slot strip 32 pivotally mounted as at 35 on a side of cushion member 31 and embracing a screw 33 which passes through strip 32 and arm 29. Said screw 70 may be adjusted by use of a hand wheel 34 adapted to clamp said strip and arm together.

75 The cushion member may be vertically adjusted by means of a hand screw 36 threadedly mounted in an enlarged portion 37 at the top of stem 18 and frictionally binding against the shaft 26. To preclude turning of said shaft upon its longitudinal axis, its formation may be hexagonal (Fig. 4) and the interior of stem 18 may be made complementary to the shaft. To sustain the 80 shaft, bracket and cushion member against uncontrolled downward movement when the hand screw 36 is loosened, an expansion spring 38 may be positioned on shaft 26, with its ends abutting the bottom portion of bracket 28 and the top of 85 the stem enlargement 37, respectively.

90 When it is desired to move the sleeve 11 pivotally on the stub shafts embraced thereby, the hand wheel 17 is turned to loosen screw 16. This movement serves to lessen the clamping action 95 of ears 13 and 14 sufficiently to permit frictional turning of the sleeve without loosening or removal of screw 15, which therefore serves as a primary while screw 16 serves as a secondary clamping means. For facilitating turning of 100 sleeve 11, a handle 39, secured to a forwardly projecting finger 40, may be provided on U-shaped bracket 28. By such movement of the sleeve 11, the cushion member may be raised and lowered 105 to a different horizontal plane and at the same 110

time, its distance relative to the chair, may be increased or decreased.

The wide range of adjustment provided in the means of this invention, makes it possible to secure perfect positioning of a patient's leg and foot. The adjustments are simple, efficient and may be effected in a minimum of time.

What is claimed is:

1. A foot and leg support for use on a chiropodist's swivel chair or the like having a step associated with the swivel portion thereof, said support comprising an inverted T joint providing a horizontal longitudinally split sleeve and a hollow upright stem, a stub shaft journaled in each end of the sleeve and projecting outwardly thereof, a pair of support rods each having one end fixed transversely in one of said projecting stub shaft ends, said rods being adapted to be adjustably secured to said chair step, means for tightening, loosening and turning the split sleeve on the stub shafts embraced thereby, an upright shaft extending through and projecting above said hollow stem and passing transversely through said sleeve between the inner ends of the stub shafts, means for securing the upright shaft in longitudinally adjusted positions in said stem, a U-shape bracket extending upwardly of the upper end of the upright shaft, an expansion spring on the upright shaft between the bracket and the upper end of said stem, a foot and leg supporting cushion member having a swivel mounting on said bracket, and means for securing the cushion member in pivotally adjusted positions.
2. A foot and leg support for use on a chiropodist's swivel chair, or the like, having a step associated with the swivel portion thereof, said support comprising an inverted T joint providing a horizontal sleeve, longitudinally split along one side thereof, and a hollow upright stem, a stub shaft journaled in each end of the sleeve and projecting outwardly thereof, a pair of support rods each having one end fixed transversely in one of said projecting stub shaft ends, means associated with said chair step for slidably holding the rods in spaced horizontal relationship with the supporting surface whereon the chair is positioned, a pair of ears disposed in vertical registration one on each side of the longitudinal split in said sleeve, means for adjusting the ears relative to one another for tightening, loosening, and turning the sleeve on the stub shafts embraced thereby, an upright shaft extending through and projecting above said hollow stem and passing transversely through said sleeve between the inner ends of the stub shafts, means for securing the upright shaft in longitudinally adjusted positions in said stem, a U-shaped bracket extending upwardly of the upper end of the upright shaft, a foot and leg supporting cushion member having a swivel mounting on said bracket, means for securing the cushion member in pivotally adjusted positions, and an expansion spring on the upright shaft between said bracket and the upper end of said stem and adapted to sustain the cushion member, bracket and up-

right shaft during adjustment of said upright shaft.

3. A foot and leg support for use on a chiropodist's chair, or the like, said support comprising a sleeve, a stub shaft journaled in each end of the sleeve and projecting outwardly thereof, means connecting the outer ends of the stub shafts to the lower portion of the chair for supporting the sleeve in spaced relationship with the chair, means for tightening, loosening and turning the sleeve on the stub shafts embraced thereby, an upright shaft extending transversely through the sleeve between the stub shafts and projecting above the sleeve, means for maintaining the upright shaft in longitudinally adjusted positions, a foot and leg supporting cushion member having a swivel mounting on the upper end of said upright shaft, and means for securing the cushion member in pivotally adjusted positions.

4. A foot and leg support for use on a chiropodist's chair, or the like, said support comprising a sleeve, shaft means embraced by the sleeve and attached to the lower portion of the chair in spaced relationship therewith for supporting the sleeve, means for securing the sleeve in adjusted positions on the shaft means, a shaft projecting upwardly from said sleeve, means for securing said shaft in longitudinally adjusted positions, and an adjustable foot and leg supporting cushion member mounted on the upper end of the upwardly projecting shaft.

5. A support for use on a chiropodist's chair or the like, and comprising a longitudinally split sleeve, a foot and leg supporting cushion member mounted on said sleeve, shaft means embraced by the sleeve and attached to the chair, a pair of ears disposed in spaced registration and in superimposed relationship with one another, one on each side of the split in said sleeve, a set of screws passing through the uppermost into the lower ear and serving as a primary clamping means, and a second screw passing through both ears and serving as a secondary clamping means, said first screw being adapted to permit frictional turning of the sleeve after loosening of said second screw which, in tightened condition, positively binds the sleeve in a given position.

6. A support for use on a chiropodist's chair or the like, and comprising a longitudinal split sleeve, a foot and leg supporting cushion member mounted on said sleeve, shaft means embraced by the sleeve and attached to the chair, a pair of ears disposed in spaced registration and in superimposed relationship with one another, one on each side of the split in said sleeve, means clamping said ears together for initially binding the sleeve on said shaft means, and secondary clamping means also operative on the ears, said initial clamping means being adapted to permit frictional turning of the sleeve after loosening of the secondary means which, in tightened condition, positively bind the sleeve in a given position.
